ROLLING MILL

Strickland Holeton, Hamburg, N. Y.

Application October 8, 1931, Serial No. 567,593

3 Claims. (Cl. 80—56)

This invention relates to improvements in rolling mills of the kind in which the rolls may be adjusted to vary the angular relation between their axes as circumstances may require.

- 5 In the rolling of sheet metal, it is desirable at times that the axes of the rolls be aligned, the sheets or packs produced when passed between the rolls having such a relation between their axes being of conventional convex cross section.
- 10 At other times, however, it is advantageous that the axes of the rolls be slightly crossed during the rolling operation, this arrangement of the rolls tending to compensate for the increased spring of the centers of the rolls and thereby reducing
- 15 the convexity of the sheets or packs. In any event, during operation of the mill, there is considerable wear upon certain parts thereof as, for example, the brasses, such wearing of the parts tending to destroy the adjusted relation in which
- 20 the rolls are operating. It will be apparent, therefore, that a mill of the type generally described not only has the advantage that it is flexible to meet different rolling requirements but also has the advantage that it is capable of adjustment to
- 25 compensate for wearing of the parts of the mill.

One object of the present invention is to provide a construction of the type generally described which is designed to enable minute adjustments of the rolls.

- 30 A further object is to provide a construction which will permit of the convenient removal of the parts of the mill in which the necks of the rolls are adjustably carried when this is necessary to effect the repair or replacement of the said parts or the repair or replacement of the rolls.

A still further object is to provide a novel construction and arrangement of the parts of the mill whereby simplicity and economy in construction are obtained.

- 40 The invention is illustrated in the accompanying drawings in which:—

Figure 1 is an end elevation of a mill construction in accordance with the invention.

- Figure 2 is a fragmentary section of the mill 45 taken along line 2—2 of Figure 1.

Figure 3 is a fragmentary section taken along line 3—3 of Figure 1.

Figure 4 is a fragmentary view partly in elevation taken along line 4—4 of Figure 3.

- 50 The invention is illustrated in connection with a four-high mill. It is to be understood, however, that this is by way of illustration only as the advantages of the invention may be obtained with its use in connection with other types of mills such as, for example, a two-high mill.

The mill, as illustrated, is provided with upper and lower working rolls 10 and 11 respectively and upper and lower companion backing rolls 12 and 13 respectively, all of the said rolls being carried in suitable housings 14. The latter are 60 of conventional form and in order to clarify illustration of the invention and avoid duplication of similar parts only one of the said housings is shown. The housing 14 is formed or provided with a window 15.

The necks 16 of the working rolls are journaled in blocks 17 which are arranged in the window 15. Each of the said blocks is substantially shorter in length than the width of the window and by virtue of the fact that the block 70 is arranged lengthwise in the window, it may be adjusted in a horizontal plane between the side walls of the window, any such movement, of course, being transmitted through the roll neck to the roll. The latter, therefore, may be adjusted in this manner so that its axis may be aligned with the axis of the companion working roll or it may be adjusted so that its axis is crossed slightly with respect to the axis of the said working roll, it being understood that in the mill illustrated such adjustment of the roll 10 will be in a substantially horizontal plane.

In order to adjust the block 17 in the manner described and in order to maintain the latter in the position to which it is adjusted, each of the said blocks is provided at opposite sides of the neck of the roll with oppositely disposed elements 18, the heads 19 of which co-operate with the side walls of the window 15. The bodies of each of the elements 18 is threaded at 20 to enable adjustment of their heads relative to the block. As illustrated, the latter is provided with oppositely disposed openings 21 in which the said elements are carried, the connection between the threaded body 20 of the elements and the block being effected through the medium of an internally threaded collar 22, the latter being suitably keyed to the body as at 23. It is to be understood that the connection between the threaded bodies of the elements and the block may be direct if the threaded collars are not desired. The openings 21 are preferably enlarged as at 24 to accommodate the heads 19 of the elements. It will be apparent that the elements 18 may be adjusted so that the distance between the faces of their heads may be substantially equal to the distance between the side walls of the window. In other words, the heads 19 of the elements extend beyond the ends of the block. Hence it will be obvious that by adjusting the elements one in one 100 105 110

direction and the other in the opposite direction the over-all distance between the faces of their heads may be maintained while the relative distances between the axis of the roll at any point within the block and the faces of the heads of the opposite elements are varied. It will be apparent that in adjusting the neck at one end of the roll in this manner that if the neck at the opposite of the roll is not adjusted in the same direction and to the same extent that the axis of the adjusted roll will be inclined relative to the axis of the companion roll. Inasmuch as the practical limits between which it is necessary that the rolls be adjustable are relatively small it is unnecessary to design the various parts especially to enable adjustments in the manner described, any such adjustments being compensated for or taken up by the various parts of the mill.

20 In order to insure ease of adjustment of the elements a lubricant may be supplied to the bodies 20 thereof through ducts 25 formed in the blocks 17 opposite the body portions, the collars 22 when availed of being formed with ducts 26 which register with the ducts 25.

25 The heads 19 of the elements are formed with a series of radially extending holes 27, preferably one or more of the said holes being accessible from the front of the housing 14. Opposite the heads 19, the blocks are cut away as at 28 to insure convenient access to the holes 27 at times when the heads 19 of the elements be substantially entirely within the body of the block, the said openings being large enough to expose a considerable part of the peripheries of the heads 22 and preferably two of the said holes regardless of the positions to which the elements may be adjusted. Thus, an element may be adjusted to effect the desired adjustment of the roll by inserting a suitable tool in an accessible hole 27 in the head of the element and then manipulating the tool to rotate the element in the direction necessary to obtain such adjustment. Thus, for example, if the adjustment of the roll is such as to require movement of the neck 16 of the roll 10 toward one of the elements, that element is rotated so that its head is moved away from the adjacent wall of the window 15. Then the opposite element is rotated so that its head is moved in the same direction, that is to say toward the adjacent wall of the window. The head of this element, however, at the time is substantially already in contact with the said wall. Upon rotation therefore, the said element, acting against the adjacent wall of the window, moves the block away from the said wall toward the opposite wall of the window and the said element is rotated until the opposite element reaches the opposite wall, at which point the parts co-operate in the desired manner. The holes 17 are preferably uniformly spaced so that they may be utilized to determine the amount of adjustment necessary, that is to say, if one element is moved through an angular distance equal to the angle between four of the holes 27, then upon movement of the opposite element through the same angular position, which movement may be determined by the holes in the said element, the heads of the two elements will co-operate in the desired manner with the walls of the window 15. After one end of the roll has been adjusted in the manner described, the opposite end of the roll may be adjusted in a similar manner, although in this case the neck of the roll will be moved in an opposite direction.

It will be apparent that owing to the direct co-operation between the elements 18 and the walls of the window 15 minute adjustments may be obtained with facility while at the same time simplicity, and hence economy, of construction is obtained.

80 Each of the blocks 17 is formed with transversely extending slots 29 in which brasses 30 fit, it being noted that the said slots are deepened adjacent the body of the roll 10 to accommodate the heads 32 of the brasses. It will be apparent, therefore, that inward movement of the block 17 is prevented by the heads of the brasses which engage the end of the body portion of the roll. Outward movement of the said block is prevented by clamps 33. The latter are secured intermediate their ends to the housing 14 as best shown in Figure 1 by studs 34 which pass through slots 35 in the clamps. The slots extend lengthwise of the clamps and hence upon loosening of the studs to a sufficient extent they may be moved outwardly in the direction of their length whereby they are removed from in front of block 16 which then may be withdrawn from the window 15. The construction described, therefore, has 100 the advantage that the parts by which adjustment of the blocks is obtained are carried by the said blocks and hence may be conveniently removed with the latter from the window when it becomes necessary to repair or replace any of such parts or to recondition or replace the rolls.

95 105 The backing rolls 12 and 13 which co-operate with the working rolls may be of conventional construction and the adjustment of the upper roll 12 is obtained in the usual manner by screws 37.

110 From the foregoing it will be apparent that the rolls of the mill may be adjusted either to meet different rolling requirements or to compensate for any wearing of the parts of the mill. The construction described enables minute adjustments of the rolls, this being primarily due to the fact that the elements by which the adjustments are made co-operate directly with the walls of the window, whereby there are no intermediate parts to provide play or lost motion between the adjusting elements and those parts of the mill which co-operate with the elements. In addition to this advantage the use of the elements in the manner described has the further advantage that a simple, and hence economical, construction is provided. 115 The various parts of the mill which carry the rolls and permit their adjustment may be quickly and conveniently removed in order to enable repair or replacement of any such parts. In the 120 illustrated embodiment of the invention both of the working rolls are shown as adjustable. It is to be understood, however, that this is by way of 125 illustration only as beneficial results may be obtained by the use of a single adjustable roll.

130 135 I claim as my invention:

1. In a rolling mill having a housing provided with a window, a pair of working rolls, means in said window in which the neck of one of said rolls is journaled and threaded elements carried by said means, said elements being formed with heads 140 which slidably engage the side walls of said window to maintain a selected axial relation between said last mentioned roll and the other of said rolls, said heads being formed for engagement with a suitable tool, whereby said element may be adjusted, at will, to vary the selected axial relation of the rolls.

145 150 2. In a rolling mill having a housing provided with a window, a pair of working rolls, means in said window in which the neck of one of said rolls

is journaled and threaded elements carried by said means, said elements being provided with headed portions which slidably engage the side walls of said window to maintain a selected axial relation 5 between said last mentioned roll and the other of said rolls, said portions being formed with radially extending holes accessible from the front of said housing and by means of which said element may be adjusted, at will, to vary the selected 10 axial relation of the rolls.

3. In a rolling mill having a housing provided with a window, a pair of working rolls, means in which the neck of one of said rolls is journaled, threaded elements carried by said means, said

elements being formed with heads which slidably engage the side walls of said window to maintain a selected axial relation between said last mentioned roll and the other of said rolls, said heads being formed with a plurality of radially extending holes and recesses formed in said means to accommodate the heads of said elements, said means being cut away adjacent said recesses to provide convenient access to said holes to permit the use of a suitable tool in adjusting said elements, whereby said elements may be adjusted, at will, to vary the selected axial relation of the rolls. 80 85
